2,536,076

DISPERSION OF SOLIDS FROM DESTROYER STACKS

Nicholas E. Oglesby, Troy, N. Y., and Fleming R. Weaver, Edgewood, Md., assignors to the United States of America as represented by the Secretary of War

Application April 27, 1931, Serial No. 533,208

12 Claims. (Cl. 114—15)

(Granted under the act of March 3, 1883, as amended April 30, 1928; 370 O. G. 757)

1

This invention described herein may be manufactured and used by or for the Government for governmental purposes, without the payment to us of any royalty thereon.

This invention relates in general to the formation of smoke screens and more particularly has reference to a method and apparatus for generating smoke clouds through the utilization of heat in waste gases.

In the past, smoke producing material has ejected in a stream of hot waste gases, such as those finding exit from the manifolds of internal combustion engines of airplanes or motors of tanks, or other vehicles, and from the stacks of ships, particularly destroyers. The methods thus far employed for carrying on the generation of smoke screens through the agencies mentioned, however, have proved generally inefficient.

Previous to this time in the dispersion of smoke producing materials in hot waste gases for finding exit in the air to form smoke screens, a solid material, for example a lacrymator of the character of chloracetophenone or a toxic material such as diphenylaminechlorarsine have been dissolved in a non-inflammable liquid and the solution sprayed into a stream of hot waste gases. By reason of the use of an inert solvent, however, the desired vaporization of the smoke producing material is exceedingly low, inasmuch as the heat required to vaporize the solvent so excessively detracts from that required to vaporize the smoke producing materials that methods of this character are manifestly inefficient because of the vast heat losses.

We propose, in order to overcome the apparently insurmountable difficulties that have heretofore been experienced in producing smoke screens by utilizing hot waste gases, to melt low melting smoke producing solids and to feed the molten material either by gravity flow or under pressure to a nozzle positioned in a stream of hot waste gases. The material may be atomized by ordinary mechanical spraying into the stream of gases or a jet of steam caused to impinge on the stream of molten smoke producing material so as to combine the mechanical force and thermal effect of the steam to atomize the material and thereby facilitate the heat transfer between the material and the hot gases of the stack to bring about a more effective vaporization than has heretofore been contemplated. Of course a suitable compressed gas may be substituted for breaking up the molten material if the use of such should be found to be more desirable than steam.

An object of this invention is to provide a

5 method of generating smoke screens by the introduction of molten smoke producing material to a stream of hot waste gases finding exit into the air where it is desired to produce a smoke cloud.

10 Another object of this invention is to provide a method of generating smoke screens by the atomization of molten smoke producing material in a stream of hot waste gases finding exit in the air where it is desired to produce a smoke cloud.

Still another object of this invention is to provide a method of generating smoke screens by the atomization with steam of molten smoke producing materials introduced in a stream of hot 15 waste gases finding exit in the air where it is desired to produce a smoke cloud.

A further object of this invention is to provide an apparatus for melting smoke producing material and for feeding the molten material to a 20 stream of hot waste gases finding exit in the air where it is desired to produce a smoke screen.

A still further object of this invention is to provide an apparatus for melting smoke producing material and for feeding the molten material into 25 a stream of hot waste gases and atomizing molten material for finding exit in the air with waste gases where it is desired to produce a smoke screen.

With these and other objects in view, which 30 may be incident to our improvements, the invention consists in the parts and combination to be hereinafter set forth and claimed, with the understanding that the several necessary elements comprising our invention may be varied in construction, proportions and arrangement without departing from the spirit and scope of the appended claims.

In order to make our invention more clearly 35 understood, we have shown in the accompanying drawings, means for carrying the same into practical effect without limiting the improvements in their useful application to the particular constructions which, for the purpose of explanation, have been made the subject of illustration.

40 There is shown in the drawings, a single figure of the apparatus forming the subject matter of this invention, from the side partly broken away, connected to the wall of a stack shown in section and broken away at the top and bottom through 45 which hot waste gases are adapted to find exit in the air. The stack may, of course, be, as is already understood, an exhaust pipe for hot waste gases on an airplane engine, or tank motor, or a stack from a ship boiler, or any

other source of power which generates hot waste gases in its operation.

Referring more particularly by numerals to the drawings, the apparatus comprises a cylindrical container 1 provided with a rounded bottom 2, and an open top formed with an outwardly extending flange 3 on the rim. A cover 4 having an outwardly extending flange 5 around the bottom rim is adapted to be seated on the top of the container and the flanges 3 and 5 formed on the container and the cover respectively, suitably secured together.

The cover 4 is formed with a central aperture in the top in which is fitted a neck 6 adapted to receive a cap 7. An annular rim 8 is fitted on the top of the neck adapted to afford a seat for the cap 7 which is provided with a downwardly extending flange 9 designed to be force fitted in the seat formed by the annular flange 8, although it may be otherwise secured, for example, by providing cooperating threads on the flange 9 and inner wall of the rim 8. A handle or other securing member 11 is connected to the top of the cap 7 to facilitate the removal of the same.

The container 1 is adapted to be supported in any suitable manner according to the particular type of installation for which it is intended. For the present purposes a plurality of angle irons 12 are secured around the circumference of the container adapted to rest on suitable supports mounted on a convenient base.

A coil 13 is mounted within the container, the top end of the coil extending through the wall of the container adjacent the rim as at 14, and the lower end projecting through the rounded bottom of the container adjacent the wall as at 15. The rounded bottom of the container is further provided with a central outlet valve 16 and the cover 4 with an inlet line 17 adjacent its periphery.

Smoke producing material such as chloracetophenone or diphenylaminechlorarsine is adapted to be introduced into the container through the neck 6 by removal of the cap 7, and steam is admitted into the coil 13 through an inlet line 18 coupled to the top end 14 through an elbow 19. The steam admitted into the coil 13 is controlled by a valve 21 interposed in the line 18. The smoke producing material deposited in the container is adapted to be melted by the circulation of the necessary quantity of steam through the coil 13 controlled by the valve 21 interposed in the inlet line 18. Waste steam together with condensate passing out of the coil through the lower end 15 is directed through a line 22, connected to the lower end of the coil by an elbow 23. The line 22 is connected by an elbow 24 to a trap 41. A line 27 is connected in the steam inlet line 18 between the valve 21 interposed therein and the top side of the coil so that steam is allowed to flow therethrough only when valve 21 is open. A line 28 is connected in the line 27 to by-pass steam therefrom through a heating jacket 29.

The molten material flowing from the bottom of the container through the control valve 16 is adapted to collect in a distributing manifold 31. The distributing manifold is connected by a plurality of lines 32, 33, and 34, having valves 35, 36, and 37 interposed therein to an outlet manifold 38 which is enclosed by the jacket 28 through which steam from the line 18 is circulated as previously stated, through the line 28 in communication with the line 27 connected to the steam inlet.

If it is desired to cleanse the system after operation of the apparatus in order to prevent the accumulation of material in the passages by solidification and to guard against injury of personnel by exposure to irritant materials in the lines, steam may be introduced therein through the line 25. The line 25, connected to the inlet line 18 below the valve 21 and having a valve 26 interposed therein, is connected to the distributing manifold 31, an additional valve 53A being interposed therein to further control the flow of steam.

The distributing manifold 31 is surrounded by a coil as indicated at 39, in which steam is circulated from the by-pass line 27. Steam is fed into this coil to heat the distributing manifold and prevent solidification of the molten material collected therein. The coil surrounding the distributing manifold is adapted to discharge waste steam and condensate into a trap 41 through lines 42A, 42B, and 42C. The trap 41 is connected at one end to the line 22 communicating with the bottom of the coil in the container, and is provided at its other end with an outlet 41a.

Steam fed into the jacket 28 to heat the outlet manifold 38 is similarly adapted to discharge into the trap 41.

Molten material introduced into the outlet manifold 38 from the container through the valve 16 and the distributing manifold 31 and selectively through the valves 35, 36, and 37, is adapted to be ejected through a line 43.

For the purpose of forcing the molten material through the system to the line 43, a pressure line 44 is connected to the inlet 17. A valve 45 is inserted in this line to control the admission of pressure. For the purpose of guarding against an excess of pressure being built up in the container 1, a safety valve 46 is also connected to the inlet 17 by means of the T-fitting 47.

The line 43 is adapted to pass through the wall of a smoke stack or conduit 48 carrying hot gases in which the smoke is to be produced. At its end within the conduit 48 the line 43 is provided with a nozzle 49 which is adapted to spray the molten smoke material into the hot gases.

Passing up through the center of the nozzle 49 is a second line 51 for a purpose which will hereinafter appear. This line 51 is connected through a line 52 to the steam line 18, a control valve 53 being inserted therein for control purposes.

The entire operation of this invention will be readily apparent from the above detailed description.

The desired smoke producing material is first introduced into the container through the neck 6, the cap 7 being removed for that purpose. The cap is then put back in place and made secure.

The steam control valve 21 is then opened, allowing steam to pass through the container coil 13, the coil 39 on the distributing manifold 31, and the jacket 28 around the outlet manifold 38. When the steam passing through the coil 13 has melted the smoke producing material within the container, the outlet valve 16 is opened, allowing the molten material to enter the distributing manifold 31. Since steam has already been allowed to pass through the coil 39 surrounding the manifold 31, this manifold will be already heated when the molten material reaches it, thus preventing any solidification of the molten material.

At this point, one or more of the valves 35, 36, 37 are opened, according to the rate at which it is desired to feed the smoke producing material into the stream of hot gases. The opening of

these valves allows the molten smoke material to pass directly into the outlet manifold 38, which has been pre-heated by the steam in the jacket 29. From the outlet manifold 38 the smoke material passes out through the line 43 to the nozzle 49 within the conduit 48.

In order to overcome the friction of the molten smoke material in flowing through the various valves, manifolds, and lines, the valve 45 in the line 44 is opened and pressure is applied through 10 line 44 to the surface of the molten material. This pressure may be controlled by the operator so as to cause the smoke material to flow at the rate desired, this control being accomplished by means of the valve 45. The safety valve 46 prevents the admission of too high a pressure into the container 1.

In order to facilitate the exhaust of the molten smoke material from the nozzle 49 and to completely atomize the same, the valve 53 is opened, thus admitting steam from the pipe 16 to pass out through the nozzle with the smoke material. This steam serves the double function of causing the molten material to be atomized and forcing it rapidly from the nozzle.

When it is desired to clean the portion of the apparatus below the valve 16, that valve is closed and valves 26 and 53A are opened. The steam from the pipe line 18 then thoroughly washes out the entire system between the valve 16 and the nozzle 49.

It will be appreciated that we have provided an apparatus for dispersing smoke producing solids in hot waste gases which eliminates the necessity of a solvent for the smoke producer.

It will also be appreciated that we have provided a method of dispersing smoke producing solids in hot waste gases in which the very state of the smoke producers when introduced into the gas stream causes them to be easily evaporated.

Furthermore we have devised a means and manner of introducing smoke producing materials into a stream of hot waste gases which atomizes such materials at the time of their introduction.

While we have used one particular construction and method for the purpose of explaining our invention, we wish it to be clearly understood that the same is by way of example only and that many modifications may be made both in our apparatus and method without departing from the spirit or scope of our invention. The scope of our invention is to be limited only by the prior art and by the terms of the appended claims.

We claim:

1. An apparatus for generating smoke clouds comprising a container, means within the container to melt normally solid smoke producing material, means to introduce predetermined quantities of molten material into a stream of hot gas of combustion finding exit in the air and means for blowing steam through the apparatus to clear the apparatus of smoke producing material.

2. An apparatus for generating smoke clouds comprising a container, a steam coil for melting smoke producing material positioned within the container, a distributing manifold connected at the bottom of the container by a line having a control valve interposed therein, means to heat the manifold line, and means to feed predetermined quantities of the molten material from the manifold into a stream of hot gas finding exit in the air.

3. An apparatus for generating smoke clouds comprising a container, a steam coil for melting smoke producing material positioned within the container, a distributing manifold connected to the bottom of the container by a line having a control valve interposed therein, an outlet manifold connected to the distributing manifold by a plurality of lines each having a valve therein, means to heat the manifolds, and means to control each valve to allow passage of predetermined quantities of molten material from the outlet manifold into a stream of hot gas finding exit in the air.

4. An apparatus for generating smoke clouds comprising a container, a source of steam supply, a steam coil for melting smoke producing material positioned within the container, and connected to the source of steam supply, a distributing manifold connected to the bottom of the container by a line having a control valve therein, the distributing manifold having a plurality of lines connected therewith having valves interposed therein, the manifold being surrounded with steam coils for heating the same, 15 a steam jacketed outlet manifold in communication with the plurality of lines connected with the distributing manifold, means to introduce steam into the coils and jacket surrounding the manifolds from the same source that supplies 20 the coil and the container and means to control the valves to introduce predetermined quantities of the molten material into a stream 25 of hot gas finding exit in the air.

5. An apparatus for generating smoke clouds comprising a container, a steam coil for melting smoke producing material positioned within the container, a distributing manifold connected to the bottom of the container by a line having a valve interposed therein, a plurality of lines 30 connected to said manifold having valves interposed therein, and a steam jacketed outlet manifold communicating with the lines and with the distributing manifold, steam coils surrounding the distributing manifold, common means to supply steam to the coils and jacket, means to jointly convey condensate and waste steam from 35 all of the coils and jackets, and means to introduce predetermined quantities of molten material into a stream of hot gas finding exit in the 40 air by manipulation of the valves.

6. An apparatus for generating smoke clouds from a ship having a smoke stack through which hot combustion gases are discharged comprising a container having means whereby normally solid smoke producing material may be introduced 45 therein, means associated with the container to heat and melt said material, means to conduct and spray said molten material into a stream of hot gas in the smoke stack finding exit in the air, and heating means for said conducting means to maintain said material molten.

7. An apparatus for generating smoke clouds comprising a container having means whereby normally solid smoke producing material may be introduced therein, means associated with the container to heat and melt said material, a pipe through which a stream of hot gases of combustion is discharged into the air, a spray nozzle positioned in the stream of hot gases, conduits 55 connecting said container and said spray nozzle, and means for heating said conduits to maintain said material molten during its passage from 60 said container to said nozzle.

8. An apparatus for generating smoke clouds comprising a container having means whereby 75

normally solid smoke producing material may be introduced therein, means associated with said container to heat and melt said material, a pipe through which a stream of hot gases of combustion is discharged into the air, a spray nozzle within said pipe, means for conducting the molten material from said container to said nozzle while heating the same, and means for simultaneously passing steam through said nozzle to atomize said material.

9. An apparatus for generating smoke clouds comprising a container having means whereby normally solid smoke producing material may be introduced therein, means associated with said container for heating and melting said material, a pipe through which a stream of hot gases of combustion is discharged into the air, a nozzle having its discharge end within said pipe, a conduit connecting said container and nozzle for discharging the molten material into the stream of hot gases, and means for passing steam through said nozzle to thereby atomize the molten material.

10. An apparatus for generating smoke clouds from a ship having a smoke stack for discharging hot combustion gases, comprising a container for receiving normally solid smoke producing material, a steam coil therein for melting the material, an atomizing nozzle within the smoke stack, piping connecting the container with the nozzle, means for heating said piping to maintain the smoke material molten, and a steam pipe connected to said nozzle for discharging steam into the nozzle whereby the smoke material is atomized and blown forcibly into the hot gases of combustion in the stack.

11. An apparatus for generating smoke clouds from a ship having a smoke stack for discharging hot combustion gases comprising a container for receiving normally solid smoke producing material, a steam coil within said container for melting the material, an atomizing nozzle within the stack, piping connecting the container and nozzle, means for heating the material during its passage through said piping to maintain it molten, a steam pipe connected to said nozzle for discharging steam into the nozzle thereby atomizing the molten material and blowing the same forcibly into the hot combustion gases in the stack, a steam connected to said piping, 50

and a valve controlling flow through said steam pipe whereby steam may be blown through said piping and nozzle to clear the same of solidified smoke material.

- 5 12. An apparatus for generating smoke clouds from a ship having a smoke stack for discharging hot combustion gases, comprising a container for melting normally solid smoke producing material, an atomizing nozzle in said smoke stack, 15 10 valved connections between said container and nozzle, and means to heat said connections to thereby maintain the material in molten state during its passage from the container to the nozzle, said atomizing means including an upwardly directed nozzle mounted in said smoke stack and spaced apart from the periphery thereof, said nozzle including a steam inlet, a steam chamber, a tubular inlet means for introducing molten smoke-producing chemical substance into said 20 chamber extending upwardly in said chamber, said chamber having an outlet axially disposed above said last mentioned inlet through which the chemical substances may be hurled upwardly and atomized by steam escaping from said chamber.
